[57] CLAIM

The ornamental design for a lifeguard-shaped pasta, as shown and described.

DESCRIPTION

FIG. 1 is a front elevational view of lifeguard-shaped pasta showing our new design, the undisclosed rear being a mirror image;

FIG. 2 is a left side elevational view thereof, the undisclosed right side being a mirror image;

FIG. 3 is a top plan view thereof; and,

FIG. 4 is a bottom plan view thereof.

FIG.3

FIG.1

FIG.2

FIG.4
